METHOD OF AND APPARATUS FOR
FACSIMILE SIGNALING

William G. H. Finch, Spuyten Duyvil, N. Y.

Application March 4, 1937, Serial No. 128,920

4 Claims. (Cl. 178—69.5)

This invention relates to facsimile systems and more particularly relates to novel methods of and means for maintaining synchronous relation between a receiver and transmitter.

Picture transmission between remote points by electrical signals requires scanning of the picture to be transmitted in a predetermined manner and entails similar scanning at a receiver or translator in proper synchronism with the transmitter scanning. Each picture may be resolved into a plurality of elemental areas. The tonations or shading of the elemental areas are translated by optical means into corresponding electrical signals of intensity varying with the tonations. At the receiver, a picture translating mechanism is used which converts the varying intensity received picture signals into corresponding shading or tonations. By maintaining predetermined and accurate synchronization between the transmitter and receiver scanning mechanisms with respect to the record sheet, a composite picture is produced at the receiver to form a facsimile of the transmitted picture.

Synchronizing systems for maintaining the receiver in step or synchronism with the transmitter have heretofore involved complex electro-mechanical mechanisms depending, in most cases, upon cyclic synchronizing signals sent by the transmitter. A commonly used system involves an electrically operated clutch at the receiver which starts up the receiver scanner at the beginning of each line of scanning at the instant a synchronizing signal is received and corresponding to the beginning of the transmission of a scanning line. Near the end of the scanning line, the receiver scanner is automatically stopped at the drum and held in this condition until the synchronizing signal releases it into action for the next scanning line.

The use of a friction clutch corresponds to the well-known start-stop synchronizing system which synchronizing system is excellent for telegraphy purposes, but is not as useful for facsimile systems. In my Reissue Patent No. 19,575 of May 21, 1935, the disadvantages of the friction clutch start-stop synchronizing systems are discussed and I disclose a start-stop synchronizing system employing a positive clutch. The positive clutch permits engagement of the scanner mechanism at a predetermined portion of the cycle and does not have the disadvantage of slipping which is inherent in the friction clutch. A modification of the positive clutch synchronizing system is disclosed in my Patent No. 2,047,863 of July 14, 1936, where an over-running

clutch is used to permit positive engagement instantaneously.

Starting and stopping of the receiver scanner mechanism to maintain synchronous movement thereof generates inertial reaction forces which cause wear and tear of the mechanism, produce noise, and also sets up vibrations at the receiver which must be damped to avoid irregularities in the facsimile reproduction. Accordingly, various attempts have been made to drive the receiver scanner by a synchronous motor which is driven by an electrical current of a frequency identical with that of the current energizing the transmitter motor. Elaborate circuits and apparatus are required by this type of synchronizing system, but for accurate reproductions, it has been, to date, the closest approach to perfect synchronous action. No noise, mechanical wear or unnecessary vibrations are set up at the receiver, and correspondingly better quality reproduction can be made. My co-pending application, Serial No. 116,302, filed Dec. 17, 1936, is an example of a direct synchronous drive for the facsimile receiver.

All the prior attempts at maintaining synchronism between the transmitter and receiver scanning mechanism depended upon the established principle of maintaining each successive line of scanning in proper phase position upon the record sheet. This principle may be expressed by stating that the beginning of each successive scanning line was required to start at the predetermined beginning edge of the record sheet. The term "phase synchronism" entails that each scanning line should be in accurate alignment with the scanning pattern so that all the shaded intonations marked on the record sheet would fall into their predetermined position and reproduce the transmitted picture. This result was accomplished by either stopping the scanner at the starting point of each line and starting it in phase synchronism in response to the synchronizing signal transmitted when the transmitter scanner reaches that predetermined position of each line, or by using a synchronous motor drive controlled by the frequency which drives a corresponding transmitter synchronous motor.

My present invention depends upon my discovery that it is not necessary to start each scanning line at the predetermined position which was heretofore thought essential, so long as each successive scanning line is displaced from the predetermined position to substantially the same degree and in progressively the same direction.

My discovery proves that the concept of phase synchronism is not limited to a predetermined vertical alignment of all the successive scanning lines but that the successive scanning lines may be displaced with respect to each other as long as the successive displacements do not exceed a reasonable amount.

The extension of the phase synchronizing principle which I have discovered may be visualized by considering a stack of thin books of the same size. By viewing the stack from one side, we have an analogy for the successive scanning lines of a picture. The prior concept of phase synchronism required that the stack be aligned so that its edges form a vertical line. In accordance with my discovery, this stack of books or scanning lines may be tilted so that the edge of the stack would be at an angle with respect to the predetermined vertical position. This tilted or angular displacement may be to the right or left of this predetermined position. Each successive scanning line, or in the analogy, book, will be displaced to the right or left of the preceding book. In a preferred condition, each successive book or scanning line is displaced in the same direction and by the same amount so that the edge defining the beginning of each scanning line or book will lie on a substantially straight line at a definite inclination or angular deviation from the predetermined vertical line position.

A facsimile reproduced in accordance with my discovered principle will be practically identical with the original reproduction but with the border line edges corresponding to the beginnings and ends of each scanning line being at an inclination to the corresponding lines of the original picture. Angular deviations as much as five to seven degrees produce negligible distortions in most applications of facsimile apparatus. I have successfully transmitted photographs, halftone pictures, black and white drawings, type-written matter and the like with my invention, and after trimming the border edges of the picture so that they are rectangular so as to correspond to the original picture, in a manner to be hereinafter described in detail, it was difficult for observers to differentiate between these novelly produced reproductions and ordinary reproductions thereof.

In accordance with my present invention, I employ the extended phase synchronizing principle which I have discovered to radically simplify the method and mechanism of maintaining a facsimile transmitter and receiver in synchronism. The receiver synchronizing mechanism is directly coupled to the driving motor and the motor is maintained at a substantially constant speed, which speed is not necessarily identical with the transmitter motor speed, but is sufficiently close to permit picture reproduction by my novel principle. As long as the driving motor speed is substantially constant, the scanner need not be periodically stopped to maintain phase synchronism as in prior devices, but the continuously rotating motor will cause the scanning lines to be successively advanced or retarded from their predetermined position by equal amounts to produce the facsimile.

No precautions need be made to maintain the receiver driving motor in perfect speed synchronism with the transmitting motor nor need any attempt be made to maintain each successive scanning line in perfect phase synchronism with the corresponding scanning at the transmitter.

The facsimile receiver of such a system is particularly simplified and the reproductions do not have any imperfections due to spurious vibrations as in prior start-stop devices. No clutch is required. The receiver is set to a speed close to the predetermined motor speed for the system and means are provided for automatically maintaining the motor at this adjusted speed which need not be identical with the corresponding speed of the transmitter motor. I also provide means for automatically starting the receiver scanning mechanism at the proper starting position on the record sheet so that the reproduction will be properly centered upon the sheet.

Accordingly, it is an object of my present invention to provide a novel method of and means for facsimile transmission and reception.

Another object of my present invention is to provide a novel method of and apparatus for maintaining a facsimile receiver in proper synchronism with the transmitter.

A further object of my present invention is to provide a novel method of and apparatus for making a facsimile reproduction.

Still a further object of my present invention is to provide a novel method of facsimile recording.

These and other objects of my present invention will become apparent in the following description of my invention taken in connection with the drawings, in which:

Figure 1 is a plan view of a preferred facsimile transmitter or receiver unit employing a mechanical governing constant speed device.

Figure 2 is a partial cross-sectional and partial elevational view of the mechanical speed control for the facsimile system of Figure 1, showing the tuning fork in position over the stroboscope disks for speed adjustment.

Figure 3 is a cross-sectional view taken along 3-3 of Figure 2.

Figure 4 is an enlarged detail of the fork prongs and slots corresponding to the view at 4-4 of Figure 2.

Figure 5 is a cross-sectional view taken along 5-5 of the fork prongs and slots at Figure 4.

Figure 6 is a diagram showing the marking strips on the stroboscope disks, in developed form.

Figure 7 is a schematic diagram of a facsimile receiving unit employing the mechanical speed control unit and having means for starting the operation at a predetermined position on the picture drum.

Figure 8 is an end view of an electrical speed governor mechanism for use in place of the mechanical governor with the cover plate removed.

Figure 9 is a cross-sectional view through the cover plate showing the contact springs and disks for the electrical governor.

Figure 10 is a partial view of a modified form of the electrical speed governor of Figure 8.

Figure 11 is a diagrammatic representation of the circuit employing the electrical speed control as incorporated in the facsimile receiver.

Figure 12 is a schematic diagram of a modified arrangement for connecting the electrical governor to control a motor circuit which governor corresponds to the illustration of Figure 10.

Figure 13 is an enlarged schematic representation of the standard scanning arrangement of a facsimile reproduction.

Figure 14 is an enlarged schematic representation, corresponding to Figure 13, to illustrate how

the same image may be reproduced in accordance with my present invention.

Figures 15 to 19 are photographic illustrations of facsimile reproductions as produced by a facsimile receiver designed and operated in accordance with my present invention. Figure 17 corresponds to the transmitted picture and is a reproduction made with perfect phase and speed synchronism. Figure 16 is a reproduction made at a scanning speed slower than the transmitter scanning speed; Figure 15 being the same picture 16 but with its borders trimmed parallel to the dotted lines. Figure 18 is a reproduction made at a scanning speed faster than the transmitter scanning speed; Figure 19 being the same picture 18 but with its borders trimmed parallel to the dotted lines.

Although the speed control and phase adjustment mechanism of my present invention is particularly useful for facsimile receivers in general, it may also be applied to the transmitter or combination transmitter and receiver units to keep the motor close to the predetermined constant speed for driving the scanning mechanism. The transmitter may be driven by a synchronous motor at the predetermined speed while the receiver is driven by the motor and control devices to be hereinafter described in more detail. Figure 1 is a plan view of a facsimile unit of the rotating drum type. It is to be understood, however, that flat-bed continuous sheet systems or other facsimile scanning methods may be employed with the synchronizing system of my present invention.

The electrical motor 20 is directly coupled to the rotatable drum 21 through reduction gearing included at 22. The drum 21 is supported by a spindle 23 operated in the tail-stock 24 and is readily removable in a manner disclosed in my Patent No. 2,047,863 referred to above. The record sheet 25 is mounted on the drum 21 by suitable sheet mounting clamps 29. The area on the record sheet 25 surrounding the clamp portion 29 is generally termed the underlap portion, at which portion of rotation of the drum 21, synchronizing signals are generated and transmitted at the transmitter and in prior systems used for periodic synchronizing at the receiver. Such synchronizing signals are transmitted at the proper time by means of a cam switch 70 actuated once per revolution of the drum. Leads 71 connect the cam switch to proper circuits for example, as shown in my Patent No. 2,047,863, already referred to. For a facsimile receiver, the cam switch 70 is used to divert the received signals to the synchronizing mechanism during the underlap period for operating the electromechanical synchronizing mechanism for maintaining accurate phase synchronism as described in the same patent. However, in my present invention, I employ the cam switch 70 at the receiver, not for cyclically maintaining synchronous conditions but for initially starting off the drum 21 so that the first line will be in proper position on the record sheet 25 in order that the picture reproduced may be centrally aligned.

Rollers 26 may be pressed against the drum and sheet 25 to assist in smooth mounting thereof. The electro-optical scanning mechanism 27 is mounted on tracks 28 in a manner to minimize transverse vibration or movement thereof with respect to the drum 21. The electro-optical scanning carriage 27 contains the optical lens system 30 for focussing the beam of light upon the record sheet 25. For a transmitter, the electro-

optical system 27 translates varying elemental shading of the picture 25 into corresponding electrical signals which are transmitted. In a facsimile receiver, the electro-optical system 27 produces a beam of light focussed upon picture 25 through lens system 30 varying in intensity in accordance with the received picture signals. A feed screw 31 is mechanically connected to the bottom of electro-optical carriage 27 and moves the carriage parallel to the axis of the rotatable drum 25 at a predetermined speed. The feed screw 31 is geared to the reduction gear box 22 by rod 32 and the gear system enclosed in housing 33. Details of the mechanical and electro-optical features of the illustrated facsimile unit are thoroughly disclosed in my Patent No. 2,047,863.

A mechanical governor 34 is shown attached to a shaft 35 extending from the drive motor 20. The mechanical governor is used to maintain the speed of rotation of the motor 20 substantially constant at the speed which the governor is adjusted to by the operator. The stroboscope disks 36 attached to the rotating system of the motor and governor have alternate black and white markings which guide the operator in the speed adjustment of the motor 20. A synchronous motor is not practicable to use for the motor 20. Motor 20 is preferably of a constant, or variable speed type which can maintain a reasonably constant speed for constant electrical and mechanical conditions. A direct current, compound or series wound motor or alternating current induction motor and the like may be used as the motor 20. Once the facsimile unit is set in operation, the speed is maintained and negligible changes in the torque demands on the motor occur. With substantially constant electrical voltage conditions, the motor will tend to rotate approximately at a predetermined speed. However, for the purposes of my invention, it is preferable to employ some speed control device to maintain the motor speed practicably as constant as possible, thus eliminating speed changes due to temperature or voltage or other variations which might occur during the progress of reproduction of a picture. In Figures 1 to 7 are illustrated details of the mechanical governor speed control; and in Figures 8 to 12, electrical governor speed control.

Figures 2 and 3 are detailed illustrations of a preferred mechanical governor attached to the extension shaft 35 of motor 20. The mechanical governor 34 comprises a friction disk or plate 37 loosely mounted upon the shaft extension 35. A plurality of leaf springs 38 are connected between the hub 39 of the disks 37 and a ring 40 secured to the rod 35 at a distance from the disk 37. Ring 40 is secured by set screw 41 to the rod 35. A weight 42 is secured to the central portion of each flexible leaf spring 38. The rotation of motor shaft 35 will cause the springs 38 and friction disks 37 to rotate therewith. The mass of the weights 42 will move outwardly due to the centrifugal force of rotation, to correspondingly deflect the leaf springs 38. The deflection of leaf springs 38 will cause the loosely mounted friction disk 37 to move closer toward ring 40 toward the right in the illustration of Figure 2. This movement of the friction disk 37 toward the right will be proportional to the speed of rotation of shaft 35 and the motor 20. A pad 43 of felt or other suitable material is set into an adjustable block 44, to coat with a surface of the friction disk 37. When the disk 37 moves sufficiently to the right, it will frictionally engage

the pad 43 and correspondingly reduce the rotation torque exercised by motor 20. By rotating the thumb screw 44 attached to the threaded rod 45 engaging the movable block 44, the operator can adjust the position of the pad 43 to control the speed of motor 20.

The speed of motor 20 is accordingly determined by the setting of the block 44 and the felt pad 43. When the speed of motor 20 exceeds the speed corresponding to the predetermined setting of the pad 43, the frictional disk 37 will be actuated with greater force against the pad due to the centrifugal action of the weights 42 and increase the frictional resistance to rotation to correspondingly maintain a substantially constant speed. In order to facilitate the setting of the pad 43 with respect to the friction disk 37, by the thumb screw 44, a pair of stroboscope disks 36 is mounted to rotate with the shaft 35. These disks contain alternate black and white markings to cooperate with the tuning fork 46 held by the operator above the rotating disk 36.

An enlarged partial plan view of the tuning fork 46 is shown in Figure 4 as consisting of two prongs 47 which may be set in vibration by striking on a flat surface. Attached to the end of the prongs are two plates 48 and 49 containing corresponding slots 50 and 51. The operator views the stroboscope disks 36 through the slots 50 and 51. Figure 5 is a cross-sectional view taken through the forked prongs and slotted plates.

The fork 46 is chosen with a natural frequency of vibration equal to a multiple or sub-multiple of the predetermined speed of rotation for the motor 20. Where greater accuracy is desired a design of fork is used which is less affected by temperature and weather variations. However, even though a small percentage of vibrational variation is to be expected from an exposed fork of this type, such variations are not at all material in view of the principle of phase synchronism which I have discovered and hereinabove described. Where a speed of 2100 revolutions per minute is used for the motor 20 corresponding to 35 revolutions per second, a tuning fork having 87.5 vibrations per second for example, may be used. The alternate black and white markings on disk 36 are arranged to permit the vibration frequency of the tuning fork to open and shut from view through the shutters 48 and 49, the markings as viewed beneath them so that when the predetermined speed is reached, the markings will appear to be stationary. To permit flexibility in the choice of fork frequency and the predetermined speed of motor 20, I use two sets of stroboscopic markings for the disk 36; one set having five alternate black and white equal length markings. Figure 6 is a development of the markings on the periphery on the disk 36. The strip 52 contains five sets of black and white marks; and the strip 53, six sets. When the speed of rotation of the motor 20 approaches substantially the predetermined speed, namely 2100 revolutions per minute, in the illustrated example, the disk containing the markings 52 of five sets of black and white markings will appear as stationary when viewed beneath the shutters 50-51 of the fork 46 vibrating at 87.5 vibrations per second.

The speed of the motor 20 is now suitable for reproduction of a picture with my facsimile system. It is not necessary to test for accurate synchronous speed with respect to the transmitter motor since the method herein described of adjusting and maintaining the speed of motor 20

constant and the new principle of phase synchronism does not require accurate synchronism. The only pre-requisite is to have a substantially constant rotative drive at a speed near the synchronous speed. The permissible degree of variation in speed is dependent upon the degree of distortion permissible at the reproduction as well as the design parameters of the facsimile receiving unit and will be discussed in detail hereinafter.

In order that the facsimile reproduction be assembled properly on the record sheet, it is necessary to have some means for starting the scanning operation so that the edge of the reproduced picture will be close to the underlap portion of the drum or otherwise close to the edge of the record sheet upon which the reproduction is made. In Figure 7 there is diagrammatically illustrated a system for automatically accomplishing this result. The motor 20 drives the picture drum 21 through the intermediate worm and worm gear arrangement 22. A practical speed for the drum 21 is 100 revolutions per minute. The mechanical governor 34 is shown attached to the extension shaft 35 of the motor 20 as already described. The electrical motor 20 is connected to a power supply by leads 54 and connection plug 55. A starting resistance 56 is connected in series with one of the motor leads 54. A short circuiting switch 57 is connected across resistance 56.

The facsimile signals are introduced to the receiver unit 58 at the input terminals 59. The signals are amplified and rectified if necessary and are further introduced to the push-pull output amplifier stage 60-61. The output amplifier 60-61 is preferably a class B amplifier where zero signal input produces zero plate current. Output transformer 62 connects the output stage 60-61 to the translating device 63. Although I schematically illustrate a neon lamp 63 for translating the facsimile signals into corresponding varying intensity light beam 64 focussed upon the record sheet 25 by lens system 65, it is to be understood that any other translating device may be employed. Thus, for example, a galvanometer light shutter or an electromechanical stylus may be used.

In order to attain the initial phase synchronism of the drum driven at constant speed by motor 20, I make use of a cyclic synchronizing signal which is transmitted in a well known manner before the beginning of each scanning line, as described hereinabove. This synchronizing signal is preferably transmitted once per revolution of the transmitting drum during the underlap portion thereof. A cam 66 is connected to the drum 21 by shaft 67 to rotate therewith. A projection 68 is made on cam 66 to open the cam switch 70 during the underlap portion of the drum 21. Cam or synchronizing switch 70 is connected across the synchronizing magnet 72 by connection leads 71. The synchronizing magnet 72 is connected in series between the return anode lead 73 of the push pull amplifier 60-61 and the anode battery source 74. When zero signal intensity is impressed upon receiver 58, zero current will flow in the synchronizing magnet 72 connected in the class B biased amplifier 60-61. During the rotation of picture drum 21, the synchronizing switch 70 will be closed and will accordingly short circuit the synchronizing magnet 72, directly connecting the battery 74 to the lead 73.

The picture signals will be transmitted to the

translating mechanism 63 and the synchronizing magnet will not be in electrical circuit connection at this time. However, at the underlap portion corresponding to the position of clamps 29, the synchronizing switch 70 will be opened by the cam nib 68 and permit the synchronizing signals to be impressed upon the synchronizing magnet 72. The synchronizing signal is of a predetermined magnitude and actuates the magnet 72 to 5 attract its armature 73 to the upper position. Armature 73 contains a switch contact 74 which coacts with a fixed contact 75. Contacts 74 and 75 are electrically connected across the resistance 56. The synchronizing armature 73 is of the 10 self-locking type, well known, for example, in the annunciator art. A leaf spring 76 is drawn to schematically indicate such a self-locking armature arrangement whereby when the armature 73 is attracted from its open position shown 15 in dotted lines at 73', it will move against the spring 76, pass the tip of the spring 76 and be locked in the closed position illustrated, closing contacts 74 and 75 to short circuit the resistor 56. I do not intend to be restricted to any specific form of locking relay-armature arrangement 20 corresponding to 72-73.

The procedure for operating the system in Figure 7 includes the step of adjusting the mechanical governor 34 close to the predetermined position by means of the thumb screw 44 and assisted by the stroboscopic action of fork 46 and disks 36. This step is performed with resistance 56 short circuited either by means of the switch 57 or the armature 73 manually placed in self- 25 locked position. The governor 34 will automatically maintain the motor 20 at the adjusted speed. The switch 57 and armature 73 are then thrown open to place the resistance 56 in circuit with the motor leads 54. The value of resistance 56 30 is designed to materially reduce the speed of the motor 20. I have satisfactorily used a value of 5 ohms for the resistance 56 in series with a driving motor using one ampere.

When the resistance 56 is placed in circuit 40 with the motor, the speed of the motor is slowed down and the mechanical governor 34 becomes inoperative at the lowered speed so as not to affect the phasing adjustment operation. During the slowing down period which starts at the 45 insertion of resistance 56, the angular position of drum 21 will progressively change until the underlap portion 29 will attain the corresponding position in time phase relation with the transmitter drum and the synchronizing signals. When 50 this period occurs, the cam 68 will open the cam switch 70 as the synchronizing signal is received to impress the signal upon magnet 72 which attracts the armature 73 in the self-locking position shown, to short circuit the resistance 56. When 55 this occurs, the motor immediately speeds up to the speed corresponding to the predetermined setting already made upon the governor 34. The phasing action is thus performed automatically since the speeding up is practically instantaneous 60 and the drum starts substantially in phase relation with the transmitter drum so that the recorded picture will be centrally aligned on the record sheet 25 as will now be evident. The shelf-locking lever 73 maintains the resistance 56 short circuited so that the mechanical governor 34 65 alone controls the speed of the motor and keeps it at the predetermined adjusted speed and substantially constant.

In order that the operator may definitely know 70 that the recording has started in phase synchro-

nism so that the picture will be properly positioned on the sheet, I provide a signal lamp 77 which will flicker when the drum is in this position. The signal lamp 77 is connected in series between a small battery 78 and contacts 79 actuated by armature 80 of solenoid 81. Armature 80 is actuated to open position by spring 82. Solenoid 81 is connected in parallel with synchronizing magnet 72 and is impressed with the synchronizing signals simultaneously with the synchronizing magnet 72. When solenoid 81 is energized it attracts armature 82 to close the circuit of the signal lamp 77 and cause lamp 77 to light. Accordingly, when the phase synchronizing operation is successfully performed and the switch 83 15 in the lamp circuit 77 is closed, the lamp 77 will flicker, being lit once per revolution of the drum, namely, one hundred times per minute in this case.

Once phase synchronism is established, the receiver drum is continuously rotated at the predetermined speed to which the motor 20 was originally adjusted and which speed is very close to the corresponding transmitter speed. Naturally if different reduction gearing ratios at 22' are used for the transmitter and receiver, the speeds of corresponding motors will be different. My present invention is concerned with operating the motor 20 at a rate close to the predetermined speed for the receiver which speed is known to the operator. After the initial phase synchronism 20 is established the recording of the picture by the translating mechanism 63 and upon the record sheet 25 is started with no further attention being required. The drum will rotate close to its predetermined rate and whether it is somewhat faster or slower than the actual speed of the transmitter drum is not important in view of my discovery. Examples of results made under different speed conditions are illustrated and 25 will be described in detail hereinafter.

After the picture reception has commenced, it is not necessary to employ the flickering light 77 and therefore I provide a switch 83 to open the circuit of the lamp 77. I also prefer to employ a switch 84 to short circuit the solenoids 72 and 81 from the anode return lead 73 of the output stage 60-61. The switch 84 is closed after the initial phase synchronism is established. The switches 57, 83 and 84 are preferably all connected to a common shaft or lever for simultaneous operation. The arrangement is such that for phasing position, switches 57 and 84 are opened and switch 83 is closed; and in running position, switches 57 and 84 are closed and switch 83 is opened.

Summarizing the operating procedure for operating the system of my present invention employing a mechanical governor speed control:

1. Insert the record sheet 25 in position on the scanning mechanism, namely the drum 21. 60
2. Close switch 57, or close contacts 74-75 by manual positioning of lever 73 into the self-locking position.
3. Adjust the mechanical governor 34 to maintain motor 20 at a predetermined speed, using 65 the fork and stroboscope disk.
4. Throw the switches 57, 83 and 84 to "phasing position," the positions illustrated in Figure 7, and open the lever 73 to the dotted position 73'. 70
5. When the signal lamp 77 starts to flicker, the drum 21 is in synchronous phase position and the system is ready for reproduction on the record sheet.
6. Throw the switches 57, 84 and 83 into "op- 75

erating position," namely closing switch 57 and 84 and opening switch 83.

I have also successfully employed electrical governors in place of the mechanical governor hereinabove described. A suitable electrical governor is illustrated in Figures 8 and 9. This governor has a pair of contacts 85. One of the contacts is fixed to a stationary post 86, the other contact being attached to a movable arm 87. A spring 88 is connected to the central portion of arm 87 to mechanically bias the arm towards the center of rotation. Arm 87 is pivoted at 89 where it is electrically connected to the post 86.

15 Hand wheel 91 is rotatably supported in a bracket 92 and is used to adjust the tension in the spring 88. Posts 86 and 90 are integral with respective conducting plates 93 and 94 for electrical connection to contact springs 95 and 96. The contact springs 95 and 96 are respectively connected to contact rings or disks 97 and 98 insulatingly supported in the end cover plate 99 for the electrical governor mechanism.

20 When the electrical governor 100 is rotated over a predetermined speed, the contacts 85 are opened due to the centrifugal action on the spring biased arm 87. An external motor control circuit is connected to the contact disks 97 and 98 for control by the speed sensitive contacts 30 85 which open when a predetermined speed is exceeded.

35 Figure 10 illustrates a modification of the governor 100 which modification reverses the contact action so that the contacts close during over speed. This modified governor 101 is similar to governor 100 except that one contact 102 is mounted by a U-shaped bracket 103 so that the contact 104 on the end of arm 87 will press against contact 82 when moved by centrifugal 40 action against the force of spring 88. The position of contact 102 is adjustable by means of thumb screw 105. An insulation block 106 is located on the conducting bracket 103 to prevent short circuiting of the arm 87 against the bracket 103.

45 Figure 11 is a diagrammatic illustration of the use of the electrical governor with a motor. This illustration employs the governor 100 illustrated in Figures 8 and 9 wherein the contacts open during over speed from the predetermined setting. The stroboscopic markings are placed on the periphery 107 of the housing for the governor 100. Contact arms 108 and 109 connect the electrical governor 100 across the resistance 110 placed in series with the motor power leads 54. When the contacts of the governor 100 are closed, the resistance 110 is short-circuited and the circuit of the motor 20 is connected directly to the power supply. When the 50 motor exceeds the predetermined speed as set by the hand wheel 91, the contacts 85 within governor 100 will open the short-circuit across resistance 110 to decrease the current supply to the motor 20. The speed of the motor 20 will be 55 momentarily decreased when the contacts 85 will close to short circuit the resistance 110. Contacts 85 are sensitive to minute speed variations and control the insertion of the resistance 110 in series with the motor to maintain the 60 average speed of the motor at the predetermined value. The inertia of the motor armature smooths out any fluctuations which the insertion of resistance 110 might cause, and produce a substantially uniform torque and speed 65 70 at the scanner driven by motor 20.

The method of initially starting the drum in phase synchronism in a manner described in connection with Figure 7 is in this case performed by the synchronizing magnet 72 and the associated electrical circuit connections with a minor difference in the connections across the motor resistance 110. Contacts 111 and 112, controlled by armature 73, are connected across the resistance 110. When the armature 73 is in open position as illustrated, the contacts 111-112 10 short circuit the resistance 110 thru a resistance 117 and permit the motor 20 to run over speed during this time. Since the contacts 85 of governor 100 are opened by the over speed condition, the motor will continue to run at over speed when contacts 111-112 are closed by lever 13. This procedure is followed to bring the drum into the initial phase synchronous condition so that when the drum is in proper phase, the synchronizing magnet 72 will become energized to attract the lever 13 into the self-locking position above spring 16 and maintain contacts 111-112 open so as to return the control of the motor speed 20 to the electrical governor 100. This procedure is similar to the procedure described 25 in connection with Figure 7 except that in this case the motor is made to over-speed instead of run at a slower speed.

30 The principle behind my preferred phase synchronizing operations resides in causing the motor and therefore the drum to run, for a short interval, faster or slower than the adjusted predetermined continuous speed in order to change the relative angular position of the drum and rapidly bring the varying drum position (with 35 respect to the corresponding transmitter drum) to a proper and initial phase synchronous condition with the transmitter drum. When the receiver drum 21 or any corresponding or equivalent scanner mechanism which may be used 40 reaches the predetermined initial phase position, the cam 66 will open the synchronizing switch 70 and remove the short-circuit across magnet 72. The transmitter synchronizing signal will cause a current to flow through the magnet 72 45 at this instant when the drum is in the proper phase synchronous condition. When magnet 72 is energized it attracts the armature 73 into a self-locking position to correspondingly return the speed control of the motor to the mechanical 50 or electrical speed governor.

Accordingly, the expedient of momentarily running the motor over-speed or under-speed after the initial setting of the governor control is to rapidly change the phase position of the 55 drum until it reaches the initial phase synchronous position, and then automatically return the control of the motor speed to the governor.

The governors will maintain the speed of the motor substantially constant for relatively long 60 periods of time, such as ten hours or even several days. Thus, once the setting of the governor is made with the stroboscopic components, it need not be readjusted at least for the run of a picture which is ten or fifteen minutes, or for the 65 operation of the receiving unit for the rest of the day. Thus in a continuous sheet recorder as disclosed in my Reissue Patent No. 19,575, an initial setting of the mechanical or electrical governor 70 for speed will suffice for many hours or even days of operation. The only procedure after the predetermined speed setting is to employ the synchronizing magnet 72 to automatically bring the phase of the drum near the underlap portion 75

at the beginning of each picture or facsimile receiving operation.

Figure 12 schematically illustrates a modified form for employing the electrical speed control. A compound wound direct current motor 20' is used having an armature 113 and a field 114. A control resistance 115 is connected in series with the field 114. The electrical governor 101 is connected across the resistance 115. This governor corresponds to the one illustrated in Figure 10 where over-speed closes the contacts and normal or under-speed maintains the contacts 102 and 104 open. When the motor 20' tends to over-speed, the contacts 102-104 short circuit the series resistor 115 thru a resistance 117 and increase the current flowing through the field coil 114 to correspondingly momentarily reduce the speed of the motor. When the speed is normal or tends to become slightly less than the predetermined setting, the contacts 102-104 will open due to the tension of spring 88 to return the resistance 115 into the field circuit. The shunt wound direct current motor will accordingly be maintained at substantially constant speed by this arrangement.

The contacts 111-112 operated by armature 73 are connected in parallel thru resistance 117 across the governor 101 and the resistance 115. The lever 73 is positioned to close the contacts 111-112 to short-circuit the resistance 115 thru the resistance 117 when the initial phase synchronizing operation is to be performed. The motor in this example will run slower than the predetermined speed until the drum is positioned in the proper phase and relay 72 is automatically energized by the synchronizing signal to attract armature 73 into the self-locking position above spring 76 and return the speed control of the motor 20' to the governor 101.

I prefer to employ a switch 116 connected in series with the circuit including contacts 111 and 112 as illustrated in Figures 11 and 12. Thus once the initial phase synchronizing operation is performed, the switch 116 may be opened to remove, in a positive manner, the effect of contacts 111 and 112 on the electrical governor. The operation of switch 116 may be performed in conjunction with the simultaneous actuation of the switches 83 and 84 in a manner already described.

My present invention depends upon the discovery of the operation of a facsimile receiver without regard to the positioning of each successive scanning line at the predetermined phase relation corresponding to that at the transmitter. Figure 13 is an enlarged diagrammatic view of the scanning of a letter H by prior facsimile systems. The scanning operation is composed by a plurality of successive scanning lines 120 illustrated by parallel dotted lines. The starting edge 121 of each scanning line 120 is aligned parallel to the left edge 122 of the record sheet 123. Each of the edges 121 are started at exactly the same distance from the sheet edge 122 and the letter H is composed by the synchronous alignment of the individual contributing segments 124 of the scanning operation. The vertical sides of the letter H are parallel to the predetermined scanning edge 121. The reproduction of the letter H as shown in Figure 13 requires accurate synchronous speed and accurate phasing of the successive scanning lines 120 with respect to the record sheet 123.

In accordance with my present invention, I maintain the scanning speed close to, but not necessarily at, synchronous speed. However, I

do maintain the scanning speed substantially constant so that whether it is slower or faster than the exact speed of the transmitter, it will remain so for the duration of the scanning operation. Figure 14 is a diagrammatic illustration of the letter H of Figure 13 reproduced in accordance with my present invention when the speed of the scanner is somewhat faster than synchronous speed corresponding to the speed of the transmitter scanner. The successive scanning lines 120 are progressively displaced to the right starting from the top. The starting point of the top scanning line 120, namely the edge 125, is shown at the correct phase position corresponding to line 121'. The edge 125 was placed at this synchronous phase position by means of the initial phasing operations and circuits including the synchronizing magnet 72 hereinabove described. However, the next succeeding edges 121 of the scanning lines 120 are each equally displaced to the right in a sort of step form when viewed in the enlarged or magnified condition. If the speed of scanning is maintained constant, the edges 121 of the scanning lines will form an angle with respect to the predetermined initial phase positions 121'. This angle has been labelled angle A for reference. I shall term this angle A the angle of distortion of the picture. The exaggerated representation of the letter H shows that the vertical sides of the letter H become parallel to the line 125' which defines the displaced edges of the scanning line 120. The horizontal member 126 of the letter H remains parallel to its original condition. Lines having intermediate angles between the vertical and the horizontal are distorted by intermediate degrees, angle A representing the maximum distortion corresponding to the vertical lines of the picture.

Figure 17 is a reproduction of the head of a kitten which I have chosen to illustrate the practical use of the principle and apparatus of my present invention. This illustration contains fine lines and much detail and requires proper phase coordination between successive scanning lines for a good quality facsimile reproduction. The photograph corresponding to Figure 17 was inserted in a transmitter and received by apparatus of my present invention. Reception with perfect synchronous speed and line by line start-stop phase synchronization methods would produce a result identical with the shape and form of Figure 17, as is evident. However, by employing the "constant speed" method of my present invention, namely setting the receiver motor at a speed close to the transmitter speed and having electrical or mechanical speed governor controls such as those described maintain the receiver scanner at a constant speed, suitable quality reproductions of the transmitted image will be produced.

In practical operation, the receiver scanner which is adjusted close to the predetermined speed by stroboscopic means or the like will not be at exact synchronous speed but either a small percentage slower or faster than the synchronous speed. The slower or faster scanning speeds will produce a corresponding slight staggering of the successive scanning lines from the predetermined position, in a manner such as described in connection with Figures 13 and 14. The angular distortion A will be proportional to the difference between the scanning speed and the synchronous speed therefor. In my experiments with my present invention, I have found that distortions corresponding to angle A of a

magnitude up to the order of 5° will hardly be recognizable as an optical distortion of a photograph even if matched or compared with the original. For many applications such as recognizable facsimile transmission and even most applications of news gathering services where received facsimiles are used as newspaper pictures, such distortions of the order of 5° and even as high as 8° produce pictures which are entirely suitable for this work and only by careful comparison with the original could distortions of some portions of the picture be recognized.

Figure 16 is a reproduction of the head of the kitten of Figure 17 as received by a facsimile receiver described in my present invention, operated at a constant speed which was somewhat slower than the synchronous speed to produce an angular distortion A of $6\frac{1}{2}^\circ$. A $6\frac{1}{2}^\circ$ distortion is unusual and was purposely made to illustrate an extreme practical case. Most tuning forks and motors and current supplies can be commercially maintained so as to produce angular distortions A within one, two or three degrees. Such small angular distortions which are the usual amount in operating my system produce negligible difference between the reproduction and the original. The illustrated distortions are purposely presented to show the extreme effects which need not be encountered in most practical cases.

The dotted lines $a-b$ and $c-d$ were drawn upon the original picture corresponding to illustration 17 parallel to the border lines of this picture. The scanning operation of the receiver which produced Figure 16 was from the left to right in the direction a to b . The system ran slower than synchronous speed and the line $a-b$, defining the relative phase displacements of the successive scanning lines was produced at an angle of $6\frac{1}{2}^\circ$ to the top border of the sheet. The reproductions of Figures 15 to 19 were made with 100 lines per inch of scanning. The face of the kitten of Figure 16, if carefully compared with the standard picture 17, may be found to have some recognizable distortions; for example, the original picture of the right eye is practically circular whereas the right eye in Figure 16 is ellipsoidal. It may also be noticed that the tip of the right ear is relatively closer to the top edge of the sheet than in the original Figure 17, due to the progressive shifting of the scanning lines in the direction $a-b$ toward the top edge.

The reproduction of Figure 16 having the relatively large angle A of $6\frac{1}{2}^\circ$ is suitable for most applications where remote photographic representation by facsimile is required. However, a better approximation to the original photograph can be made by trimming the reproduction of Figure 16 along lines parallel to the lines $a-b$ and $c-d$ which is parallel to the distortion. Figure 15 is the identical facsimile reproduction of Figure 16 having an angle A of $6\frac{1}{2}^\circ$ but having the top and bottom border edges trimmed along the corresponding dotted lines $a-b$ and $c-d$. The vertical sides of Figure 15 were trimmed perpendicular to these edges to produce the frame of Figure 15 for direct comparison with the original Figure 17. It will be noted that the tip of the right ear in Figure 15 is returned to its original relative position as seen in Figure 17; even though the right eye has been made ellipsoidal this distortion becomes less noticeable when compared to the original as seen in Figure 15. Although I have shown Figure 15 being trimmed parallel to the actual distortion lines $a-b$ and

$c-d$, it is obvious that intermediate degrees of trimming may be used, which trimmings may be dictated by the actual photograph in hand.

However, I wish to emphasize that in most practical reproductions there is hardly a need for trimming operations. Such angular trimming may be expedient where larger angles have been incurred. Since most transmitted pictures have their original border lines corresponding to the frame of the original orientation of the picture, and since these border lines appear upon the facsimile reproduction corresponding for example to the line $a-b$ of Figure 16, a direct guide is thus afforded to the operator of the amount of distortion his picture has. This line which becomes part of the facsimile reproduction may be used as a border line for trimming the picture received.

Figure 18 illustrates the reception of the photograph of Figure 17 by the same receiver which produced Figure 16 but operated at a scanning speed somewhat faster than the original or synchronous speed. The dotted line $a'-b'$ and $c'-d'$ correspond to the lines $a-b$ and $c-d$ of Figure 16 which lines define the original border edges of the transmitted picture. The distortion which I have induced in Figure 18 is 8° , an amount which is practically never met with in commercial operation since the apparatus can readily be brought closer to the predetermined speed than the amount necessary to produce 8° distortion. However, this exaggerated distortion is presented to illustrate that a usable photograph is produced even with larger distortions so long as the scanning speed remains substantially constant. The recognizable features of the kitten or any photograph reproduced by such distortions, is made possible by the extended principle of necessary phase synchronization which my present invention is based upon. Since each successive line is progressively staggered by a like amount, the distorted reproduction is a usable photograph.

In the distortion of Figure 18, it will be noted that the right ear is further away from the top edge of the sheet as compared to the original Figure 17. It will be recalled that the opposite angular distortion shown in Figure 16 produced a reverse effect, namely that the right ear became closer to the top border edge. Comparing the tip of the left ear in Figures 16 and 18 will show the obvious relative misplacement of this portion of the picture. Another recognizable distortion of Figure 18 is the left eye of the kitten as viewed in the photograph. The left eye in this case has become more ellipsoidal than the original left eye. A flatter ellipse for this eye is produced in Figure 18 as compared to the elliptical distortion of the right eye of Figure 16 due, first of all, to the greater over-all angular distortion and due to the fact that the original left eye is somewhat ellipsoidal in shape.

Figure 19 is the same photograph of Figure 18 at an 8° distortion but having its borders trimmed along the lines $a'-b'$ and $c'-d'$ to bring the distortion of the photograph closer to the original by this amount. It will be seen that the vertical dark portion of the kitten's nose is at an angle to the vertical in the Figure 19 as compared to the vertical position thereof in the original Figure 17. The exaggerated distortion of 8° for Figure 19 makes the appearance of the kitten clearly distinguishable from the original Figure 17. However, this distortion is not serious for many applications of facsimile systems even for

newspaper work. By trimming the exaggerated distorted picture of Figure 18 intermediate between the lines $a'-b'$, $c-d'$ and the borders thereof, a compromise may be struck between the vertical distortions of the picture and the horizontal displacement after trimming to even afford a more favorable comparison with the original photograph.

Accordingly, it will now be evident that my present invention provides a material simplification of facsimile receivers for quality facsimile reproductions. My present system eliminates the necessity for start-stop phase synchronization at each line employing clutches and the like; eliminates the requirement for use of synchronously driven motors at the identical speed of the transmitter; and employs relatively simple substantially constant speed motors controlled by relatively simple electrical or mechanical governors to maintain a reasonably constant speed.

Although I have illustrated my present invention utilizing motor drives having a constant speed as controlled by electrical and mechanical governors, it is to be understood that a constant motor speed independent of external governor control may be practically used. For example, a direct current motor, preferably of the compound wound type driven by a storage battery having a substantially constant voltage, will maintain excellent operating constant speed for the purposes of my present invention. After the motor has run for several minutes, the temperature conditions are stabilized for the substantially constant voltage source and load. A rheostat connected in the motor circuit to manually adjust the speed thereof is necessary, the speed adjustment being determined by the tuning fork and stroboscope disk. By using a constant voltage source, the necessity for a speed governor is thus eliminated.

It will be evident that means other than the stroboscope and tuning fork arrangements may be used to apprise the operator when the motor is adjusted to substantially the predetermined speed of operation. Once the speed is adjusted close, not necessarily at the predetermined speed, the receiver is prepared for the initial phasing operation in a manner hereinabove described. The facsimile reproduction will bear a distortion angle A of magnitude depending upon the difference between the operating or adjusted receiver scanning speed and the predetermined scanning speed at the transmitter. The system of my present invention produces a progressive staggering of the scanning lines when the receiver scanning speed is different than the original scanning speed, but due to the constant speed and no interruption of the scanner, the staggered lines form a regular pattern and combine to produce a reproduction, the edges of which are at a small angle from the predetermined position but, on the whole, producing a facsimile which in most cases is difficult to distinguish from the original.

Although I have described preferred methods of and apparatus for carrying out the principle of my present invention, variations thereof will be evident to those skilled in the art, and accordingly, I do not intend to be limited except as set forth in the following claims.

70 I claim:

1. In a facsimile system provided with a transmitter comprising a picture scanning mechanism,

motive means for operating said mechanism at a predetermined rate, means for generating electrical signals in accordance with the elemental shading of a picture to be transmitted and means for generating predetermined cyclic signals in accordance with the transmitter scanning operation; a receiver comprising a scanner; a motor directly geared to said scanner and operable at a substantially constant rate independent of said predetermined rate; means responsive to said cyclic signals for predetermining the initial phase position of the receiver scanning operation; a speed changing means connectible in the motor circuit for changing the motor speed from said constant rate; and means operable by the cyclic signal responsive means for rendering said speed changing means ineffectual whereby said motor is returned to said substantially constant speed when the scanner is placed in initial phase synchronism.

2. In a facsimile receiving system, a scanner; a motor directly geared to said scanner; means for operating said motor at a substantially constant rate independently of the transmitter scanning rate during the translation of the picture for aligning the successive scanning lines progressively in one direction; and means operative on said motor for automatically predetermining the initial phase position for the directly geared receiver scanner operation.

3. In a facsimile reproduction system, a scanner; an electric motor directly geared to said scanner for driving said scanner; means for operating said motor at a substantially constant rate independently of the transmitter scanning rate comprising a speed governing device mechanically connected to said motor and electrically connected in the motor circuit, means for predetermining the initial phase position of the directly geared receiver scanning operation including a synchronizing magnet, a resistance connectible in the motor circuit for changing the motor speed, and means operable by said magnet for disconnecting said resistance from the motor circuit whereby the speed control of said motor is returned to said speed governing device when the scanner is initially in phase synchronism.

4. In a facsimile system provided with a transmitter comprising a picture scanning mechanism, motive means for operating said mechanism at a predetermined rate, means for generating electrical signals in accordance with the elemental shading of a picture to be transmitted and means for generating predetermined cyclic signals in accordance with the transmitter scanning operation; a receiver comprising a scanner; a motor directly geared to said scanner and operable at a substantially constant rate independent of said predetermined rate; means responsive to said cyclic signals for predetermining the initial phase position of the receiver scanning operation; a speed changing means connectible in the motor circuit for changing the motor speed from said constant rate; and means responsive to said speed changing means for rendering said speed changing means ineffectual whereby said motor is returned to said substantially constant speed when the scanner is placed in initial phase synchronism; and means responsive to said synchronizing signals for indicating when the receiver scanner is in phase synchronism with the transmitter scanning mechanism.

WILLIAM G. H. FINCH.
